RACK FOR GARDENING TOOLS

Lloyd E. Yetter, Colchester, Ill.

Application July 5, 1957, Serial No. 46,834

Term of patent 14 years

(Cl. D35—1)

Figure 1 is a perspective view of a rack for gardening tools showing my new design.

Figure 2 is a front elevational view thereof with a portion of the supporting standard broken away for convenience of illustration.

Figure 3 is a side elevational view taken from the right of Figure 2, and,

Figure 4 is a bottom plan view of Figure 2.

I claim:

The ornamental design for a rack for gardening tools, substantially as shown.
